UNITED STATES PATENT OFFICE.

WILLIAM WILSON HAMILL, OF GLASGOW, SCOTLAND.

CARBURETER FOR INTERNAL-COMBUSTION ENGINES.

1,020,198.

Specification of Letters Patent. Patented Mar. 12, 1912.

Application filed February 26, 1910. Serial No. 546,172.

To all whom it may concern:

Be it known that I, WILLIAM WILSON HAMILL, a subject of the King of Great Britain, residing at Glasgow, Scotland, have 5 invented certain new and useful Carbureters for Internal-Combustion Engines, of which the following is a specification.

This invention relates to improvements in carbureters and is applicable to internal combustion or explosion engines of all types, 10 more particularly to engines using heavy liquid hydrocarbon fuels, and has for its object to improve the construction of same and to provide simple and more efficient means 15 whereby the density and temperature of the mixed gases supplied to the engine are automatically maintained constant, and whereby the proportion of hydrocarbon to air may also be controlled independently when required.

My invention also insures a homogeneous mixture of the gases, and provides a corrective means whereby the volume of the mixed gases is automatically regulated and proportioned during sudden variations in the requirements of the engine, such as when suddenly slowing down from its accelerated speed to its minimum, and whereby the tendency to flooding or "pooling" due to the 25 inertia of a column of liquid fuel emitted through an unrestricted jet orifice, is entirely obviated, giving practically perfect combustion at all times; this flooding, in the ordinary jet, interfering with proper combustion by giving a charge of gas excessively rich in hydrocarbon, and causing incomplete combustion, smoky exhaust and fouling of the cylinder and valves.

In order that my invention may be clearly 30 understood I have hereunto appended the accompanying sheets of drawings, whereon:

Figure 1 is a sectional elevation of the improved carbureter. Fig. 1^a is a front view of 35 the door 7. Fig. 1^b shows a slight modification. Figs. 2, 3, 4 and 5 are detail views of the spraying nozzle *a*, double truncated cone piston *j*, and throttle valve spindle *n*, hereinafter referred to. Fig. 6 is a detail view 45 of a modified form of the double truncated cone piston *j* hereinafter described.

On the drawings the same reference letters wherever repeated indicate the same or similar parts.

Under my invention the carbureter comprises a spraying nozzle *a* which is sur-

rounded by two semi-cylindrical and detachable covers *b*, the head of the spraying nozzle *a* having a number of radial orifices *c* at right angles to its axis, and its axial passage *d* being closed at its upper end, preferably by a screw *e* which can be removed for cleaning purposes, and being provided with the usual needle valve *f* at its lower end for controlling the fuel inlet. The head of the spraying nozzle *a* is surrounded by an outer concentric sleeve *g* which tapers toward its upper end and is formed with an internal annular groove or recess *h* and a number of small radial outlets *i*, the said sleeve *g* being 60 adapted to close or open the spraying nozzle orifice *c*. Surrounding said sleeve *g* is a double conical or truncated-cone piston *j* and air is drawn in between this cone *j* and the sleeve *g* into an upper compartment *k* of 65 the carbureting chamber, (Fig. 1) the minor diameter of said cone *j* in its normal position being coincident with the center of the fuel outlets *i*, and said cone *j* having a cross-head or spider *l* which is connected to a central spindle *m* adjustably connected to an outer concentric throttle valve spindle *n*, the 70 position of these spindles *m* and *n* being regulated by nuts *o* and *p*, the construction being such as to allow adjustment of any element while the engine is running and without interfering with or fouling any of the other parts. The double truncated cone piston *j* is, or may be, provided also with a series of 75 orifices or slots *q*, as shown in Fig. 6, the air 80 entering the orifices *q* and mixing with the fuel above the fuel outlet orifices *i* without 85 increasing the suction at the fuel outlet orifice.

In the arrangement shown in Fig. 1^b the 90 lower part of the cone piston *j* is provided with orifices *q*, these orifices *q* being adapted to communicate with a recess *r* in the upper compartment *k*, when the cone piston is raised as shown in dotted lines, thereby 95 admitting air above the spraying nozzle *a*. The sleeve *g* surrounding the spraying nozzle *a* is formed integral with a bridle *r* which crosses the spider or crosshead *l* at right angles, the upper boss or collar *s* of 100 the said bridle *r* sliding on an extension of the hollow throttle valve spindle *n* and being held in its normal position by a spiral spring *u* on the throttle valve spindle *n*. On the throttle spindle *n* is mounted a piston throttle valve *v* which slides in a concentric throttle sleeve *w* having ports *t*, this 105 110

sleeve w being fixed into an ordinary valve chamber x (Fig. 1) by a flange y which is used to locate the whole apparatus centrally in the upper compartment k and which acts as a stop for lugs z provided about midway on the aforementioned bridle r the said valve chamber x communicating with the outlet to the engine manifold. The piston throttle valve v is provided, at its upper 10 end, with an outwardly turned rim or flange 1 which acts as a stop, in its normal position, by abutting on the upper rim of the throttle sleeve w , and, on the upper extremity of the throttle spindle n , a collar 2 or 15 other suitable means is provided for raising and lowering the hollow spindle n , this collar 2 being operated either by hand from a suitable controlling lever 2^a or by automatic means, such as the engine governor. The 20 lower compartment 3 of the carbureting chamber is surrounded by a hollow jacket 4, which is in connection with the main exhaust pipe 5 for the purpose of heating the carburetor, the temperature of said jacket 25 4 being controlled by a thermostat of any suitable type, and a swivel door or cover 7 is provided to give access to the interior of the jacket 4. The swivel door 7 (see also Fig. 1^a) is hinged at 31, and is provided 30 with a bridge piece 32 which is adapted to engage a pin 33 on the casing 34, a screw 35 and handle 36 being provided whereby the door 7 is caused to make an air-tight joint with the casing 34 when the handle 36 is 35 given a slight turn. The hydrocarbon is heated before admission to the lower compartment 3 by passing through a jacket 8, surrounding the exhaust pipe 5, thereby raising the temperature of the fuel to that 40 at which vaporization will readily take place, while the air is drawn in through a jacket 8^a surrounding the exhaust pipe 5 and is thereby heated and passes at a very high velocity around the nozzle a . 45 The operation of my improved carburetor is as follows:—In its normal position, or when the engine is at rest, the spraying nozzle orifices c are closed by the surrounding sleeve g , but on the throttle valve spindle n being raised slightly, the groove h and outlets i in the sleeve g come into communication with the orifices c , thus admitting the hydrocarbon to the upper compartment k of the carbureting chamber, air passing 50 between the sleeve g and the surrounding cone j and mixing with the hydrocarbon, and, in this position, the lugs z on the bridle r abut against the flange y fixed in the upper compartment k , thus limiting the upward movement of the sleeve g and bridle r , while the piston throttle valve v being slightly raised, opens communication by the ports t of the sleeve w from the upper compartment k to the engine cylinder. As the 55 engine increases in speed the valve spindle 60 65

n is further raised, thus drawing up the cone j and increasing the area between it and the sleeve g of the spraying nozzle a , and admitting more air to the upper compartment k , which, by reason of the increased suction, draws more hydrocarbon in with it, thus maintaining the proper proportion of air to fuel. The ports of the sleeve w are further uncovered, as the spindle n and throttle valve v continue to rise 70 until the ports are full open or until the required volume of the mixed gases is entering the combustion chamber, while, at the same time, the spring u on the spindle n is compressed against the boss s of the bridle r . When the engine speed is reduced, the mechanism controlling the engine closes the throttle valve v , and the cone j moves vertically downward, thus reducing the air supply, and, as the throttle valve v and cone j are nearing the end of their downward movement, the spring u on the valve spindle n relaxes. When the boss of the throttle valve v abuts against the upper boss or collar s of the bridle r , the sleeve w and bridle r are moved downward, thus covering or partially covering the orifices c , as desired, and thereby cutting off or restricting the fuel supply and preventing excess of oil in the upper compartment k . 95

By my improved construction of carburetor the proportion of hydrocarbon to air is automatically controlled and the density maintained constant at all speeds of the engine, thus giving practically perfect combustion, but, if desired, the proportion of hydrocarbon to air may also be controlled independently when required, as for example, when using oils of varying constituencies by adjusting the relative positions of the central spindle m and the outer concentric throttle valve spindle n . 100

Having now fully described my invention what I claim and desire to secure by Letters Patent is:— 110

1. The combination, with a carburetor for internal combustion engines having a chamber, a fuel spraying nozzle arranged in said chamber, a double cone piston surrounding said nozzle and means for moving said piston longitudinally of said nozzle, of a sleeve movably fitted upon said nozzle for regulating the fuel supply, means for moving said sleeve in conjunction with said piston and means for stopping the movement of the sleeve while the piston continues to move, relative adjustment being thereby obtained between the piston and sleeve. 115

2. The combination, with a carburetor for internal combustion engines having a chamber, a fuel spraying nozzle arranged in said chamber, a double cone piston surrounding said nozzle and means for moving said piston longitudinally of said nozzle, of a sleeve movably fitted upon said nozzle for regu- 120 125 130

lating the fuel supply, means for moving said sleeve in conjunction with said piston and means for stopping the movement of the sleeve in one direction and checking its movement in the other direction independently of the movement of the piston.

3. The combination, with a carbureter for internal combustion engines having a chamber, a fuel spraying nozzle arranged in said chamber, a double cone piston surrounding said nozzle and means for moving said piston longitudinally of said nozzle, of a sleeve movably fitted upon said nozzle for regulating the fuel supply, means for moving said sleeve in conjunction with said piston, means for stopping the movement of the sleeve in one direction and elastic means for checking its movement in the other direction independently of the movement of the piston.

20 4. The combination, with a carbureter for internal combustion engines having a carbureting chamber, a fuel spraying nozzle arranged in said carbureting chamber, a double cone piston surrounding said nozzle and means for moving said piston longitudinally of said nozzle, of an outer concentric and tapering sleeve movably fitted upon said nozzle for regulating the fuel supply, means for moving said sleeve in conjunction with said piston and means for stopping the movement of the sleeve while the piston continues to move, relative adjustment being thereby obtained between the piston and sleeve.

35 5. The combination, with a carbureter for internal combustion engines having a carbureting chamber, a fuel spraying nozzle arranged in said carbureting chamber, a double cone piston surrounding said nozzle and means for moving said piston longitudinally of said nozzle, of an outer concentric and tapering sleeve movably fitted upon said nozzle for regulating the fuel supply, means for moving said sleeve in conjunction with said piston and means for stopping the movement of the sleeve in one direction and checking its movement in the other direction independently of the movement of the piston.

50 6. The combination, with a carbureter for internal combustion engines having a carbureting chamber, a fuel spraying nozzle arranged in said carbureting chamber, a double cone piston surrounding said nozzle and means for moving said piston longitudinally of said nozzle, of an outer concentric and tapering sleeve having fuel outlet orifices therein and movably fitted upon said nozzle for regulating the fuel supply, means for moving said sleeve in conjunction with said piston and means for stopping the movement of the sleeve while the piston continues to move, relative adjustment being thereby obtained between the piston and sleeve.

7. The combination, with a carbureter for internal combustion engines having a carbureting chamber, a fuel spraying nozzle arranged in said carbureting chamber, a double cone piston surrounding said nozzle and means for moving said piston longitudinally of said nozzle, of an outer concentric and tapering sleeve having fuel outlet orifices therein and movably fitted upon said nozzle for regulating the fuel supply, means for moving said sleeve in conjunction with said piston and means for stopping the movement of the sleeve in one direction and checking its movement in the other direction independently of the movement of the piston.

8. The combination, with a carbureter for internal combustion engines having a carbureting chamber, a fuel spraying nozzle arranged in said carbureting chamber, a double cone piston surrounding said nozzle, and a spindle connected to and adapted to raise and lower the said piston longitudinally of said nozzle, of an outer concentric and tapering sleeve slidably fitted upon the nozzle and having fuel outlet orifices therein, a spindle concentric with the first-mentioned spindle, a bridle fitted upon said second spindle and connected to and adapted to raise and lower the said piston and means on the bridle for stopping the movement of the sleeve while the piston continues to move, relative adjustment being thereby obtained between the piston and sleeve.

9. The combination, with a carbureter for internal combustion engines having a carbureting chamber, a fuel spraying nozzle arranged in said carbureting chamber, a double cone piston surrounding said nozzle, and a spindle connected to and adapted to raise and lower the said piston longitudinally of said nozzle, of an outer concentric and tapering sleeve slidably fitted upon the nozzle and having fuel outlet orifices therein, a spindle concentric with the first-mentioned spindle, a bridle fitted upon said second spindle and connected to and adapted to raise and lower the said piston and means on the bridle for stopping the movement of the sleeve in one direction and checking its movement in the other direction independently of the movement of the piston.

10. In a carbureter for internal combustion engines, the combination of a fuel spraying nozzle having outlet orifices therein, an outer concentric and tapering sleeve slidably fitted upon the nozzle and having fuel outlet orifices therein, a double truncated cone piston surrounding said sleeve, a spindle, a bridle fitted upon said spindle and connected to and adapted to raise and lower the said sleeve, a second spindle connected to and adapted to raise and lower the said double cone piston, and a throttle valve mounted on said first spindle.

11. In a carbureter for internal combus-

- tion engines, the combination of a fuel spraying nozzle having outlet orifices therein, an outer concentric and tapering sleeve slidably fitted upon the nozzle, and having 5 fuel outlet orifices therein, a double truncated cone piston surrounding said sleeve, a spindle, a crosshead mounted on said spindle and connected to said double cone piston, a tubular spindle fitted upon said 10 first spindle and adjustable thereon, a bridle fitted upon and connected to said sleeve, means for raising and lowering said spindles and means on the bridle for stopping the movement of the sleeve while the piston 15 continues to move, relative adjustment being thereby obtained between the piston and sleeve.
12. In a carbureter for internal combustion engines, the combination of a fuel spraying nozzle having outlet orifices therein, an outer concentric and tapering sleeve slidably fitted upon the nozzle, and having 20 fuel outlet orifices therein, a double truncated cone piston surrounding said sleeve, a 25 spindle, a crosshead mounted on said spindle and connected to said double cone piston, a tubular spindle fitted upon said first spindle and adjustable thereon, a bridle fitted upon and connected to said sleeve, means for rais- 30 ing and lowering said spindles and means on the bridle for stopping the movement of the sleeve in one direction and checking its movement in the other direction independ- 35 ently of the movement of the piston.
13. In a carbureter for internal combustion engines, the combination of a fuel spraying nozzle having outlet orifices therein, an outer concentric and tapering sleeve slidably fitted upon the nozzle and having 40 fuel outlet orifices therein, a double truncated cone piston surrounding said sleeve, a spindle, a crosshead mounted on said spindle and connected to said double cone piston, a tubular spindle fitted upon said 45 first spindle and adjustable thereon, a bridle fitted upon and connected to said sleeve, a 50 spring fitted upon the tubular spindle and interposed between bosses on said bridle and tubular spindle, and means for raising and lowering said spindles.
14. In a carbureter for internal combustion engines, the combination of a fuel spraying nozzle having outlet orifices therein, an outer concentric and tapering sleeve 55 slidably fitted upon the nozzle and having fuel outlet orifices therein, a double truncated cone piston surrounding said sleeve, a spindle, a crosshead mounted on said spindle and connected to said double cone piston, a tubular spindle fitted upon said 60 first spindle and adjustable thereon, a bridle fitted upon said tubular spindle and connected to said sleeve, a spring fitted upon the tubular spindle and interposed between 65 bosses on said bridle and tubular spindle, a
- throttle valve mounted on said tubular spindle, an outer concentric and ported throttle valve sleeve, lugs on said bridle adapted to engage with the lower end of said valve sleeve, a rim on said valve 70 adapted to engage the upper end of said valve sleeve, and means for raising and lowering said spindles.
15. A carbureter for internal combustion engines having, in combination, a chamber, 75 a fuel spraying nozzle arranged in said chamber, a sleeve movably fitted upon said nozzle for regulating the fuel supply, a double cone piston exterior of said sleeve for regulating the air supply and dividing the said chamber into upper and lower compartments, a piston throttle valve located in the upper compartment of the chamber and means for operating said sleeve, piston and throttle valve.
16. A carbureter for internal combustion engines having, in combination, a chamber, 80 a fuel spraying nozzle arranged in said chamber, a sleeve movably fitted upon said nozzle for regulating the fuel supply, a double cone piston exterior of said sleeve for regulating the air supply, a spindle, a bridle fitted upon said spindle and connected to and adapted to raise and lower the said sleeve, a second spindle connected 85 to and adapted to raise and lower the said double cone piston, and a throttle valve mounted on said first spindle.
17. The combination, with a carbureter for internal combustion engines having a carbureting chamber, a fuel spraying nozzle therein, of a sleeve movably fitted on said nozzle for regulating the fuel supply to the carbureting chamber, a perforated double cone piston movably fitted within 90 the carbureting chamber and exteriorly of said sleeve for regulating the air supply to the carbureting chamber, and means for moving said sleeve and piston longitudinally of said nozzle to regulate the fuel and air supply.
18. The combination, with a carbureter for internal combustion engines having a carbureting chamber, a fuel spraying nozzle therein, of a sleeve movably fitted on 95 said nozzle for regulating the fuel supply to the carbureting chamber, a double cone piston having a series of inclined perforations therein said piston being movably fitted within the carbureting chamber and dividing the said chamber into upper and lower compartments, means for moving said sleeve and piston longitudinally of said nozzle to regulate the fuel and air supply, and a recess in the said upper compartments 100 adapted to communicate with the said perforations when the piston is raised thereby admitting air above the said spraying nozzle.
19. A carbureter for internal combustion 105

engines having, in combination, a chamber, a fuel spraying nozzle arranged in said chamber, a sleeve movably fitted upon said nozzle for regulating the fuel supply, a 5 double cone piston exterior of said sleeve and having orifices therein, said piston regulating the air supply, and means for operating said sleeve and piston.

20. A carbureter for internal combustion engines having, in combination, a chamber, a fuel spraying nozzle arranged in said chamber, a sleeve movably fitted upon said nozzle for regulating the fuel supply, a double cone piston exterior of said sleeve 10 and having orifices therein, said piston regulating the air supply, a mixing chamber having a recess therein and located above said spraying nozzle, and means for 15 operating said sleeve and piston.

21. A carbureter for internal combustion engines having, in combination, a chamber, a fuel spraying nozzle arranged in said chamber, a sleeve movably fitted upon said nozzle for regulating the fuel supply, a double cone piston exterior of said sleeve 20 and having orifices in the lower part thereof, said piston regulating the air supply, a mixing chamber having a recess therein and located above the spraying nozzle, a piston 25 throttle valve located in the mixing chamber and means for operating said sleeve, piston and throttle valve.

In testimony whereof I affix my signature in presence of two witnesses.
